UNITED STATES PATENT OFFICE.

JOHN W. COAST, JR., OF TULSA, OKLAHOMA, ASSIGNOR TO THE PROCESS COMPANY, A CORPORATION OF MARYLAND.

ART OF CRACKING HYDROCARBONS.

1,348,267.

Specification of Letters Patent.

Patented Aug. 3, 1920.

Application filed April 9, 1917, Serial No. 160,822. Renewed June 14, 1920. Serial No. 389,009.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Cracking Hydrocarbons, of which the following is a full, clear, and exact description, reference being had to the accompanying 10 drawings, forming a part of this specification.

My invention relates to improvements in the art of cracking high boiling point petroleum hydrocarbons. In cracking hydrocarbons of this kind to obtain "cracked" gasolene it has been found necessary to condense the unconverted, or partially converted, high boiling point fractions before they reach the condenser from which the low 20 boiling point product is recovered. In actual practice, the vapor is usually conducted away from the still and then through one or more reflux condensers whereby the high boiling point fractions are condensed, the 25 condensate being conducted from the reflux condensers to the still for further treatment.

The main object of this invention is to condense the high boiling point fractions in the upper portion of the still, permitting 30 the condensate to drop back into the liquid, and conducting the remaining vapor from the still to the condenser, from which the product is recovered. To accomplish this, the upper portion of the still is maintained 35 in a relatively cool condition, the vapor being deflected and conducted along the cool portion of the still in such a manner that the temperature of all of the vapor is very materially reduced, thereby condensing the 40 high boiling point fractions before the vapor passes from the still. Owing to the peculiar manner in which the vapor is baffled, deflected, and brought into contact with the cool parts of the still, the temperature of the 45 vapor may be reduced to such a low degree that only the desired low boiling point fractions will escape from the still. In this event, it will be unnecessary to pass the vapor through the ordinary reflux condensers.

In the preferred form of the invention, a relatively cool fluid, preferably a high boiling point hydrocarbon liquid, is introduced into the vapor confined in the still. This 55 liquid serves as a condensing medium for the

vapor, and it is eventually vaporized and cracked in the still. The vapor is also, preferably, subjected to the action of relatively cool steam before it escapes from the still.

Figure I is a diagrammatical view of a 60 cracking apparatus adapted for use in carrying out my method.

Fig. II is an enlarged transverse section taken through the middle portion of the still, showing the baffles and the restricted 65 vapor passageways at the upper portion of the still.

Fig. III is an enlarged longitudinal section of the still.

To illustrate the invention, I have shown 70 a cracking still 1, in the form of a large boiler, arranged above a heating chamber 2, and connected by means of a vapor pipe 3 to a water cooled condenser 4 from which the low boiling point product is recovered. 75

The apparatus shown is particularly adapted for use in cracking high boiling point products of distillation, such, for example, as the distillates or residues resulting from the distillation of crude petroleum. 80 The contents of the still are, of course, maintained under pressure, and any desired pressure may be obtained by regulating a valve 5 in the vapor pipe 3. The pressure in the still is preferably greater than 50 pounds 85 per square inch, for example, about 80 pounds per square inch, and the temperature of the liquid contents of the still preferably ranges from about 600° F. to about 800° F. The low boiling point vapor, passing from the liquid, flows through the relatively cool upper portion of the still and is discharged into the vapor pipe 3. The relatively high boiling point fractions are condensed in the still, as will be hereinafter described, and permitted to drop back into the liquid. This high boiling point condensate includes some heavy coke-forming fractions commingled with lighter fractions which may be redistilled to form a part of the low 90 boiling point product.

The end portions of the still bottom are seated upon the walls 6 of the heating chamber 2, and these walls protect said end portions from the intense heat of the heating 105 chamber. The heat is transmitted directly through the middle portion of the still bottom, and the protected end portions of said bottom are maintained in a relatively cool condition.

The vapor cooling means includes a large vapor trap, in the form of an inverted trough, located in the upper portion of the still. This vapor trap comprises a longitudinal baffle member 7 which extends approximately from one end of the still to the other, said baffle member being semi-circular in cross section so as to conform approximately to the shape of the top wall of the still. The baffle member 7 is separated from the top wall of the still to form a restricted vapor passageway 8. End baffle members 9, located at the ends of the long baffle member 7, are separated from the end walls of the still to form restricted passageways 10 for the rising vapor flowing to the restricted passageway 8. The lower edges of the end baffle members 9 are located above and adjacent to the surface of the liquid in the still to form restricted outlet ports 11 for the vapor flowing to the end passageways 10.

An air cooled tower 12 extends upwardly from the top wall of the still to receive the vapor flowing from the long restricted passageway 8. 13 designates a baffle device arranged in the air cooled tower and separated from the upright wall thereof to provide a restricted annular passageway 14 for the rising vapor. The baffle device 13 is in the form of a receptacle, open at the top to receive the vapor and closed at the bottom to exclude the rising vapor.

To prevent the vapor from escaping around the lower longitudinal edges of the long baffle member 7, these edges are preferably located below the level of the liquid in the still, as shown most clearly in Fig. II. Condensate troughs 15, located adjacent to the longitudinal edges of the baffle member 7, are inclined toward the ends of the still. The condensate, flowing from the baffle member 7, drops into the troughs 15, and the heavy coke-forming fractions contained in the condensate are thereby conducted to the end portions of the still, where they will settle upon the still bottom at points above the walls 6. These heavy fractions drop by gravity, and they accumulate on the protected portions of the still bottom, instead of being permitted to collect at points where the heat is transmitted to the still.

Instead of being protected, the upper portion of the still is subjected to the cooling action of relatively cool air currents. A jacket 16, approximately semi-circular in cross section, is preferably arranged over the correspondingly shaped upper portion of the still to provide an air passageway 17, and air under pressure may be discharged from a pipe 18 to the passageway 17 for the purpose of creating a forced draft of cool air over the top wall of the still. A 65 perforated discharge pipe 19, located in the

restricted passageway 8, is connected to a supply pipe 20 through which a relatively cool fluid is conducted for the purpose of cooling the vapor. This relatively cool fluid is, preferably, a high boiling point hydrocarbon liquid, and it is discharged through the numerous perforations in the pipe 19 so as to cool the vapor, at the same time cooling the upper portion of the still. This hydrocarbon liquid, in addition to serving as a cooling medium, is subjected to the cracking process carried on in the still, and it eventually forms part of the low boiling point product.

A perforated discharge member 22 (Fig. III), arranged in the cylindrical baffle device 13, is connected to a steam pipe 23 provided with a regulating valve 24. Relatively cool steam, passing from the discharge member 22, is forced into the vapor in the cylindrical baffle device 13.

The vapor rising from the liquid under the long baffle member 7 is trapped by the baffles 9. This vapor passes under the lower edges of the end baffles 9, upwardly through the restricted end passageways 10, through the long restricted passageway 8 above the baffle 7, thence upwardly in the restricted passageway 14, downwardly in the cylindrical baffle device 13 and then into the vapor pipe 3. The upper portion of the still is maintained in a relatively cool condition, as previously pointed out, and the vapor is baffled, deflected, brought into contact with the cool parts of the still, and otherwise acted upon in such a manner that the temperature of all of the vapor is greatly reduced. As a consequence, the high boiling point hydrocarbons are condensed in the still, and all of the vapor escaping from the still may be condensed in the water cooled condenser 4 from which the cracked product is recovered.

The condensate formed in the cylindrical baffle device 13 passes through a liquid seal or trap 25 and drops onto the long baffle member 7. The high boiling point condensate formed in the restricted passageway 8, between the top wall of the still and the baffle 7, flows downwardly on the top face of the baffle 7 and commingles with the liquid in the still. The heavy coke-forming fractions are conducted, by the inclined troughs 15, to the end portions of the still, where they drop by gravity to the protected end portions of the still bottom.

In treating petroleum hydrocarbons to obtain "cracked" gasoline, the object is to recover all of the vaporized fractions having a normal boiling point lower than about 500° F. The fractions having higher boiling points should be continually subjected to the high pressure and high temperature in the still for the purpose of converting them into lighter fractions. By reducing

the temperature of the vapor in the still as herein shown and described, all of the vaporized fractions having a normal end or dry point higher than 500° F. may be condensed in the still. All of the vapor passing from the still will then be free from the undesirable heavy fractions, and the desired product may be obtained by condensing all of this vapor in the water cooled 10 condenser 4.

The condensing action at the upper portion of the still can be varied by regulating the flow of relatively cool steam, air or liquid, each of which serves as a cooling 15 medium for the vapor. It will, therefore, be apparent that the apparatus can be easily adjusted or regulated to condense, or "knock back" all of the fractions having a boiling point higher than about 500° F.

20 I claim:

1. In the art of cracking petroleum hydrocarbons, the method which comprises vaporizing a hydrocarbon liquid in a horizontal cylindrical still, maintaining the 25 liquid and vapor under pressure, maintaining the upper portion of the still in a relatively cool condition, deflecting vapor to an end portion of the still and then along the relatively cool upper portion so as to condense the vaporized fractions having relatively high boiling points, and conducting the remaining vapor from the still to a condenser.

2. In the art of cracking petroleum hy-

drocarbons, the method which comprises 35 vaporizing a hydrocarbon liquid in a horizontal cylindrical still, maintaining the liquid and vapor under pressure, maintaining the upper portion of the still in a relatively cool condition, deflecting vapor to an 40 end portion of the still and then along said relatively cool upper portion, into an air cooled tower at the top of the still, thence upwardly along the upright wall of said tower and downwardly near the center of 45 the tower, thereby condensing the vaporized fractions having relatively high boiling points, and conducting the remaining vapor from said air cooled tower to the condenser.

3. In the art of cracking petroleum hydrocarbons, the method which comprises 50 vaporizing a hydrocarbon liquid in a still, maintaining the liquid and vapor under pressure, forcing relatively cool air along 55 the outer face of the upper portion of the still, introducing a relatively cool fluid into the still at the upper portion thereof, trapping the vapor and deflecting it to the relatively cool upper portion of the still, then 60 conducting the vapor along said relatively cool portion so as to condense the fractions having relatively high boiling points and conducting the remaining vapor from the still to the condenser.

In testimony that I claim the foregoing I hereunto affix my signature.

JOHN W. COAST, JR.
